UNITED STATES PATENT OFFICE.

JAMES A. JOHNSON, OF STOCKVILLE, NEBRASKA, ASSIGNEE OF ONE-HALF TO
ELLIWORTH D. BROWN, OF STOCKVILLE, NEBRASKA.

TRAIN SIGNALING APPARATUS.

1,237,628.

Specification of Letters Patent. Patented Apr. 27, 1916.

Application filed March 10, 1914. Serial No. 332,731.

To all whom it may concern:

Be it known that I, JAMES A. JOHNSON, a citizen of the United States of America, residing at Stockville, in the county of Fremont and State of Nebraska, have invented and useful Improvements in Train Signaling Apparatus, of which the following is a specification.

This invention relates to improvements in train signaling apparatus and has particular application to an automatic train carried signal whereby the engineer or motorman as the case may be will be notified in the event of his train passing a danger signal.

In carrying out the present invention, it is my purpose to provide a signal apparatus of the class described which will be under the control of the road signal system and which will embrace the desired features of simplicity, efficiency and durability, which may be installed and maintained at a minimum expense and which will operate effectively under all weather conditions.

With the above and other objects in view, the invention consists in the construction, combination and arrangement of parts hereinafter set forth and falling within the scope of the claim.

In the accompanying drawings, Figure 1 is a transverse sectional view through a trackway and motor car thereon showing my invention installed. Fig. 2 is a diagrammatic view of the track device. Fig. 3 is a similar view of the car carried mechanism. Fig. 4 is an end view of the car carried circuit closer. Fig. 5 is a longitudinal sectional view therethrough. Fig. 6 is a view in elevation of the track instrument.

Referring now to the drawings in detail, 1 designates a trackway which, in the present instance, is divided into blocks and equipped with some suitable form of block signaling system. Located adjacent to the entrance to each block and in proximity to the particular semaphore of the road signaling system is an electroresponsive device 2 comprising a partially circular core 3 carrying a winding 4 and having the opposite ends thereof equipped with pole pieces 5, 5 of opposite polarity and designed to set up a magnetic flux or field. This electromagnetic device is disposed proximity to one line of rails of a trackway and the terminals of the winding thereof are connected in an electric circuit 6 including a suitable source

of energy as a battery 7 and a circuit closer 8 under the control of the signal blade of the adjacent semaphore and adapted to close the circuit 6 when the signal blade is moved to the danger position so as to energize the winding of the electroresponsive device whereby the magnetic field will be set up.

In the embodiment of my invention selected for illustrative purposes, the car carried mechanism is shown as applied to a steam locomotive and comprises an electromagnet 9 and a circuit breaker 10 embodying an electromagnet 11, an armature 12 pivoted at one end and disposed within the influence of the pole of the magnet and equipped with a push button 13 and having the outer end thereof adapted to engage a stationary contact 14. Disposed within the influence of the electromagnet 9 is an armature 15 connected through the medium of a cord 16 with the whistle 17 of the locomotive and adapted to be actuated by a spring 18 when the magnet 9 is deenergized, the spring 18 swinging the armature 15 to exert a pull upon the cord 16 and thereby cause the sounding of the whistle 17. The windings of the magnets 9 and 11 are connected in series in an electric circuit including a conductor 19 extending through the winding of the magnet 9 and connected with the contact 14 and a conductor 20 connected with the pivoted end of the armature 12 and extending through the winding of the solenoid 11 and including a suitable source of energy as a battery 21. The terminals of the conductors 19 and 20 are connected with a circuit breaker carried by the locomotive and adapted to respond to the magnetic field set up by the electroresponsive devices along the trackway. This circuit breaker comprises a casing 22 composed of brass or other non-magnetic material, and a magnetizable element 23 disposed within the casing and formed of soft iron or other metal capable of being highly magnetized.

Secured to one end wall of the casing 22 and disposed within the influence of one of the poles of the core 23 is a metallic disk 24, while depending from a blank 25 secured to the end wall of the casing 22 in proximity to the disk 24 is a contact lever 27 disposed in a plane parallel with that of the disk 25 and having one end thereof formed to provide a contact 28 adapted to engage a contact 29 carried by the disk 25 and normally

held in engagement with such contact. Threaded through the lever 27 is an adjusting screw 30 by means of which the frictional contact between the lever and the disk 5 may be varied so as to eliminate the possibility of the contacts 28 and 29 separating in the travel of the car.

From the foregoing description taken in connection with the accompanying drawings, the construction and mode of operation of my train signaling apparatus will be readily apparent. When a signal is set at danger the circuit 6 is closed and the electro-responsive device energized with the effect 5 to set up a magnetic field. As a train passes the danger signal the casing 22 containing the element 23 passes through the field set up by the energized solenoid whereby the pole of the element 23 adjacent to the disk 20 25 acts upon the latter to separate the contacts 28 and 29 thereby breaking the circuit including the magnets 9 and 11. As the magnet 9 is deenergized the spring 18 reacts to exert a pull upon the armature 15 thereby opening the whistle 17, while when the magnet 11 is deenergized the armature 12 is relieved of the influence of the pole of such magnet and the spring 31 connected with such armature swings the latter to open

position, thus holding the circuit including 30 the conductors 19 and 20 and the battery 21 open when the element 23 passes out of the influence of the field set up by the energized electroresponsive device along the track.

It will be seen that I have provided a 35 train signaling apparatus whereby the engineer or motorman will be advised when his train has passed a danger signal.

I claim:

In train signaling apparatus, a track 40 electroresponsive device comprising a core curved longitudinally in the form of a semi-circle, poles at the ends of said core, a winding encircling said core, means for energizing said winding to set up a magnetic 45 field between said poles, a circuit breaker, and a magnetizable element controlling said circuit breaker and movable through said magnetic field whereby the circuit breaker will be opened to break the controlled circuit.

In testimony whereof I affix my signature in presence of two witnesses.

JAMES A. JOHNSON.
